UNITED STATES PATENT OFFICE.

HUGH MISCAMPBELL, OF DULUTH, MINNESOTA.

CONCRETE-MIXER.

No. 801,329.

Specification of Letters Patent.

Patented Oct. 10, 1905.

Application filed October 23, 1902. Serial No. 128,457.

To all whom it may concern:

Be it known that I, HUGH MISCAMPBELL, a citizen of the United States, residing at Duluth, in the county of St. Louis and State of Minnesota, have invented certain new and useful Improvements in Concrete - Mixers; and I do hereby declare the following to be a full, clear, and exact description of the invention, such as will enable others skilled in the art to which it

10 appertains to make and use the same.

This invention relates to improvements in apparatus for mixing concrete and similar substances.

It consists in an annular receptacle with a 15 revoluble floor mounted on a suitable base, a stationary frame positioned over such receptacle, from which frame depend stirring-plows attached to beams secured to the frame in such manner as to permit of their oscillation with- 20 in assigned bounds.

It consists, further, in the interposition of cushion-blocks between the beams, to which the plows are attached, and the surfaces limiting the oscillation of said beams.

25 It consists also in the positioning of trap-doors in the revoluble floor of the aforementioned annular receptacle, together with improved and convenient means of operating such doors, so as to permit the ready dis- 30 charge of the concrete or other mixture therefrom.

It further consists in certain other novel constructions, combinations, and arrangements of parts, as will be hereinafter more fully de- 35 scribed and claimed.

In the accompanying drawings, Figure 1 is a top plan view of a concrete-mixer embodying the present invention. Fig. 2 is a vertical central section through the same. Fig. 3 40 is an inverted plan view of the floor of the said mixer. Fig. 4 is an enlarged detail view of a portion of the plow-frame, showing the manner of securing the individual plows thereto. Fig. 5 is a detail view of one of the tripping mechanisms for engaging the trap-door-operating devices. Fig. 6 is a detailed view of the mechanism for operating the scraper. Fig. 7 is a detail view of the trap-door-latching device. Fig. 8 is a detail view of the 45 trap-door-closing device. Fig. 9 is a detail view of one of the latches for the swinging doors. Fig. 10 is a detail perspective view showing the shaft and arms for operating one of the doors. Fig. 11 is a detail perspective view of one of the anchoring-plates of the floor-bracers.

In mixing concrete or other similar substances it is desirable to have the mechanism for accomplishing the result so constructed that the condition of the materials being operated upon may be apparent to the eye of the operator at all times. I find by the use of my improved mixing apparatus that I am enabled to mix large quantities of concrete at one time in an even and thorough manner and yet have 60 the whole mass within the vision of the party superintending the operation, so that he can see whether the material is too wet or too dry, for instance, or whether it is needful to add a little more of one material or of another. 70

In developing the invention along practical lines I employ an open floor or platform, as 1, which is supported upon a suitable framework 2, preferably formed of beams or girders extending radially beneath the same. The 75 frame 2 is provided upon its under side with an annular track or grooved plate, as 3, which faces an upwardly - projecting similarly-grooved annular plate 4, arranged upon the foundation 5 of the machine. Balls forming 80 ball-bearings, as at 6, are interposed between the grooved plates to form a supporting ball-bearing for the frame 2 and the floor 1. The said floor and the frame carrying the same are thus mounted so that they may be revolved 85 upon said ball-bearing above the foundation 5 of the machine. A vertical central standard or post 7 is mounted upon the foundation 5 and extends upwardly through the center of the floor-frame 2, passing through suitable 90 bearings, as 8 and 9, secured to the said floor-frame. The bearing 9 is formed in a strengthening-plate 10, which is located upon the upper surfaces of the beams composing the frame 2. In order to strengthen the said frame, I 95 preferably arrange bracing-yokes 11 so as to inclose a portion of the said beams, the lower portion of each loop or yoke engaging a detent, as 12, secured to the lower faces of the beams of the frame 2. Each yoke ex- 100 tends thence upwardly, one leg thereof upon each side of its respective beam, the upper ends of the said yoke projecting through apertures formed in the annular rim of the brace-plate 10, where they are secured in place by 105 suitable nuts. The floor-frame may thus be thoroughly braced with respect to the center bearing of the device.

The floor 1 is provided at its outer edge with an upwardly-extending annular wall 13, 110 and near its inner edge at a point a suitable distance from the post 7 the said floor is pro-

vided with an upwardly-extending inner wall 14. These walls form an annular compartment or receptacle, together with the floor, upon the floor-frame. The floor-frame 2 is also provided with suitable means for rotating it upon its bearings. While a variety of rotating means might be employed, I prefer to secure an annular rack, as 15, beneath the floor-frame at its outer edge, the said rack being adapted to engage an actuating-pinion 16, secured to a shaft 17 upon the foundation 5. This shaft 17 preferably carries a bevel gear-wheel 18, meshing with a bevel-pinion 19 upon a counter-shaft 20^a. The counter-shaft 20^a also carries fast and loose pulleys, as at 21^a, by which it may receive motion through a suitable belt from any source of power. The relative sizes of the gears 18 and 19 will control the speed imparted to the table 1. The standard 7 projects above the table 1 and its inclosing walls 13 and 14 and is adapted to support a frame, as 20, which carries suitable mixing or stirring means. The frame 20 is formed of a series of outwardly-extending beams, as 21 21, which are held in position at the center of the machine by upper and lower hub-plates 22 and 23. These hub-plates are splined to the standard 7, so that the frame may be raised or lowered upon the said standard, but will not revolve about the same. The frame 20 is adjustably secured to the standard 7 by attaching the upper hub-plate through the agency of links or chains 24 24 to the inner bifurcated ends 25 of an adjusting-lever 26. This lever 26 is fulcrumed to a bracket 27, rigidly secured to the upper end of the standard 7. The lever 26 is made sufficiently long to project beyond the edges of the table 1 and the foundation-frame 5, so that an operator or attendant may, by grasping the outer end of the said lever, raise or lower the frame 20 with respect to the floor 1. The timbers or beams of the frame 20 carry upon their under edges segmental frames, as 28, 29, and 30. These segmental frames are preferably struck from different centers, being arranged upon the arcs of different circles. Each frame is preferably formed of outer and inner curved pieces of angle-iron, as 31 and 32, which are bolted to the beams 21 of the frame 20, and are further strengthened by being connected with each other by a lattice-work of cross and diagonal bars 33 and 34. These segmental frames therefore serve to brace the outer ends of the beams composing the frame 20. The frame 29 is preferably arranged so that it connects one end of the frame 28 with one end of the frame 30. The other ends of the frames 28 and 30 are arranged at a suitable distance from each other, being separated or isolated. These segmental frames I employ to carry the stirring means used above the floor 1. While any suitable stirrers may be employed for this purpose, I find that superior results are

obtained by using plows, as 35 35. These plows are formed with upwardly-extending stems, as 36, which are secured to or formed integral with approximately horizontally extending supporting-beams 37. The beams 37 are preferably secured to the lattice-work of the segmental frames 28, 29, and 30. The manner of their attachment is such that the said beams will be allowed a small amount of oscillation. One end of each of the said beams 37 is pivoted to a lug 39, which is secured to the under side of one of the lattice-bars 33. The said beams 37 are supported near their other ends within loops 38, formed upon suitable plates which are bolted to the lattice-bars. These loop-plates preferably have interposed between them and the lattice-bars cushion-blocks, as 40, preferably formed of rubber or other elastic material. The beams 37 thus have a slight motion upon their fulcrums, the movement of the same being limited by the loops 39. This permits the plows to yield somewhat when necessary, should they be caught in any manner upon the table. The construction of the whole plow-frame is such that when it is lowered all the plows will be brought near the surface of the floor and in position to stir or mix the materials carried around by the said floor. Although the plows on the frame may be arranged at any desired angles, they are preferably not turned much from coincidence with concentric lines on the floor. All the plows are arranged so that no one follows in the same path traveled by another, so that the whole floor will be thoroughly covered by their operation. It is desirable, however, to arrange the plows upon one of the segments—say segment 29—so that it will turn their furrows in an opposite direction to the furrows turned by the plows upon the other segment. This arrangement further assists in the thorough mixing of the materials upon the table. When the frame carrying the plows is raised out of contact with the floor, it may be held in said raised position by causing the lever 26 to engage a hook 41 or any other suitable means secured to the frame 20 or elsewhere. When the frame is to be lowered, it is merely necessary to disengage the lever 26 from said hook and allow the lever to move upwardly.

In order to facilitate the discharging of thoroughly-mixed materials on the floor 1, I provide said floor with one or more trap-doors, as 42 42, only one of these doors being illustrated in the drawings, since it is deemed sufficient to illustrate the construction so as to be readily understood by those skilled in the art. I find that the use of three such doors is ordinarily sufficient to accomplish the desired purposes. These doors are preferably equidistant from each other and are hinged at one of their edges, as at 43, to the edge of the aperture in the floor which they are designed to close. These hinges are preferably of the 13c

piano-hinge style, so that no crevices will be left for the material to work through. The doors 42 are held in their closed positions by means of suitable latches or sliding bolts, 5 preferably as at 44 44, the said latches moving in inclosing housings, being pressed outwardly by springs located behind them. Each of the bolts 44 is provided with a shank or stem, which is connected with a chain, as 10 45, which chain is adapted to be secured to a windlass-rod, as 46, there being one windlass-rod for each trap-door. Each windlass-rod is mounted in suitable bearings beneath the floor and extends nearly to the periphery of 15 said floor, but, preferably, not across said rack 15, where it is provided with a trigger or operating-lever 47. A trip-block or obstacle, as 48, is pivoted to the foundation-frame 5, so as to be in the path of the triggers 47 and in position 20 to move the same to one side as the table revolves for rocking the windlass-shafts. When a windlass-shaft is thus rocked, the bolts 44 44 of the adjacent door will be retracted and the door will be permitted to fall 25 by gravity, swinging downwardly upon its hinge. Each door is also provided with means for raising it again to its closed position, which means consists in a rock-shaft 49, secured to the under side of the floor in suitable bearings 30 arranged upon the opposite side of the door from the latches. Each rock-shaft 49 carries one or more levers or arms 50, which are arranged to press against the under surface of its particular door. The rock-shafts 49 extend 35 nearly to the periphery of the floor 1, but preferably not across said rack 15, and are also provided with triggers 51 for rotating the said rock-shaft, the said triggers being similar to the triggers 47 of the windlass-shaft 46. These triggers 51 are arranged to 40 be engaged by a trip-block 52, somewhat similar to the trip-block 48 and also secured to the foundation-frame 5 in the path of said triggers. In order that the trip-block 48 may 45 not engage the triggers 51 of the closing devices, the said trip-block 48 is arranged at a greater distance from the periphery of the floor than the trip-block 52, which is designed 50 to operate the said triggers 51. All the windlass-shafts are therefore extended correspondingly nearer to the periphery of the table than 55 are the rock-shafts 49.

Since it is not desired to open the doors except at the end of the mixing operation, the 55 trip-blocks 48 and 52 are so formed that they may be quickly thrown out of operative position. Each of these trip-blocks is pivoted at one end to the frame 5. Each block is formed with a tripping end, as 53, which projects upwardly from the plane of the pivoted end portion. By this shape it is possible to swing the trip-blocks back and forth into and out of operative position. When the block is in the 60 position shown in full lines in Fig. 5, its tripping end portion will engage the triggers of

the door-operating mechanisms. When the block is swung either inwardly or outwardly upon its pivot, the tripping end portion will not engage the triggers of the door-operating mechanisms.

The foundation-frame 5 is preferably formed with an open portion, as at 54, to receive the discharged material from the floor 1, the said open portion of the frame also facilitating the removal of the said material 70 75 from the machine. The trip-blocks are arranged so that the latches 44 will be released just as the door begins to pass over the open space 54, while the trip-block 52, which closes the doors, is arranged upon the other side of 80 the said opening, thus giving ample opportunity for the material to pass through the open trap.

In the use of such a mixing apparatus it is also needful to have proper means for the 85 spreading of material upon the floor when newly discharged thereon and for scraping material from the said floor when the trap-doors are opened. This I accomplish by arranging a scraper, as 55, above the floor 1 at 90 a point to one side of the discharge-opening 54. This scraper 55 is suspended upon a rock-shaft 56, which extends across the upper portion of the inclosure formed by the walls 13 and 14 and is pivoted at its inner end in a 95 fixed collar 57, secured to the standard 7, while the outer end of the said shaft finds a bearing in a post 58, arranged upon the base-frame 5. In order to operate the scraper, the outer end of the shaft 56 is provided with a 100 crank-arm 59. This crank-arm may have an operating-handle, if desired, but is preferably connected by means of a link 60 with a vertical lever 61, fulcrumed upon the base of the machine below the said rock-shaft. The use 105 of the lever 61 makes it possible to control the scraper with sufficient power to hold it firmly against the action of the material carried by the floor. It is only necessary to move the scraper about ninety degrees in 110 order to accomplish all the desired results. When the scraper is raised to a horizontal position, it will permit the material upon the floor to pass beneath it untouched; but when the said scraper is brought to a vertical position 115 it will be in a position to remove all the material from the said floor through the open doors. By holding the scraper at intermediate points it may be made to even or smooth the surface of and properly distribute the 120 material upon the floor.

The operation of the machine in mixing concrete is somewhat as follows: Gravel and cement are introduced upon the table—say, from overhead troughs or other similar 125 means—as the table revolves, the scraper being lowered sufficiently, if desired, to operate as a spreader of the material. The handle of the forked lever 26 is then released and the plow-frame lowered until the mixing- 130

plows enter the materials for producing the concrete, the said mixing-plows and frame being non-revoluble while said table revolves in a direction opposite to the direction of the plow. During the mixing of the material water is applied from a hose to the required amount. When sufficiently mixed, the plow-frame is raised and the frame-lever secured by the hook 41, so that the said frame will remain in its raised position. The trip-blocks are then set so as to engage the triggers first of the windlass-shafts and then of the rock-shafts for closing the doors. As the traps are successively opened over the space 54 the scraping-board is lowered, and all material is thus forced to pass through the open doors as the floor revolves. After each door has discharged the material brought over it the triggers of the closing-rod will engage their trip-blocks, and the doors will be lifted, so as to be engaged by the locking-bolts again. After all the material has been scraped from the floor through the traps and the traps have been closed the trip-blocks are thrown out of position until another batch of concrete has been mixed. A new supply of material can then be placed upon the table and the mixing operation repeated. In the meantime the concrete discharged into the opening 54 may be removed from beneath the machine.

From the above description it will be evident that a machine of this character can be advantageously used for mixing concrete and like material, since the operation of the whole machine is entirely within the control of attendants, and the process can be carried on under the eye of an experienced person. By this means the concrete can be mixed neither too wet nor too dry, and the proper ingredients can be used in the required quantities.

Having now described my invention, what I claim as new, and desire to secure by Letters Patent, is—

1. In a concrete-mixer, the combination of

a base, a revoluble floor mounted thereon, a non-revoluble frame positioned above said floor, depending stirring-plows provided with beams pivotally secured to said frame at their forward ends, and limiting-loops secured to said frame and loosely engaging said beams intermediate of their ends, substantially as described.

2. In a concrete-mixer, the combination with a base of a revoluble floor mounted thereon, a non-revoluble frame positioned above said floor, stirring-plows depending toward said floor from said frame and provided with beams pivotally secured to said frame at their forward ends, limiting-loops secured to said floor and loosely engaging said beams intermediate of their ends, and cushions interposed between said beams and said frame, substantially as described.

3. In a concrete-mixer, the combination of a skeleton base, a revoluble floor mounted thereon, trap-doors positioned in said floor and hinged at one of their edges, spring-latches for holding the doors in closed position windlass-shafts connected with said latches by flexible means adapted to be wound upon said shafts, triggers attached to said windlass-shafts, adjustable trip-blocks adapted to be brought into the path of said triggers to operate said windlass-shafts, and retract said spring-latches, rock-shafts secured to said floor and provided with arms for closing said doors, triggers secured to said rock-shafts for operating the same, adjustable trip-blocks adapted to be brought into the path of the last said triggers to operate the same, and means for revolving said table, substantially as described.

In testimony whereof I hereunto affix my signature in presence of two witnesses.

HUGH MISCAMPBELL.
